UNITED STATES PATENT OFFICE

166,227

GATELEG TABLE BASE

Albert Sachs, Chicago, Ill.

Application November 3, 1951, Serial No. 17,251

Term of patent 7 years

(Cl. D33—14)

To all whom it may concern:

Be it known that I, Albert Sachs, a citizen of the United States, residing at Chicago, in the county of Cook and State of Illinois, have invented a new, original, and ornamental Design for a Gateleg Table Base, of which the following is a specification, reference being had to the accompanying drawing, forming part thereof.

In the drawings:

Figure 1 is a side perspective view of a gate-leg table base showing my new design;

Figure 2 is an end perspective view thereof;

Figure 3 is a perspective view showing the legs of the table base in an outwardly swung position; and

Figure 4 is a top plan view on a reduced scale.

I claim:

The ornamental design for a gateleg table base, substantially as shown.

ALBERT SACHS.
